United States Patent Office

Des. 218,683
Patented Sept. 15, 1970

218,683

CHAIR

Robert E. Kjer Jakobsen, Compton, Calif., assignor to Schlumberger Limited (Schlumberger, N.V.), New York, N.Y., a corporation of the Netherlands Antilles

Filed June 2, 1969, Ser. No. 17,437

Term of patent 14 years

Int. Cl. D6—01

U.S. Cl. D15—1

FIG. 1 is a front perspective view of a chair in accordance with my design;

FIG. 2 is a rear perspective view thereof; and

FIG. 3 is a side perspective view thereof.

The characteristic feature of the design resides in the backrest member as best illustrated in FIGS. 1 and 2.

I claim:

The ornamental design for a chair, substantially as shown and described.

UNITED STATES PATENT OFFICE
CERTIFICATE OF CORRECTION

Design No. 218,683

Robert E. Kjer Jakobsen

September 15, 1970

It is certified that error appears in the above identified patent and that said Letters Patent are hereby corrected as shown below:

In the heading to the printed specification, lines 3 to 5, "assignor to Schlumberger Limited (Schlumberger N.V.), New York, N. Y., a corporation of the Netherlands Antilles" should read -- assignor, by mesne assignments, to Daystrom Virtue, Inc., Houston, Tex., a corporation of Texas --.

Signed and sealed this 2nd day of March 1971.

(SEAL)
